PANEL METER FOR AN AMMETER OR THE LIKE

Roger B. Kerr, Marblehead, Mass., assignor to General Electric Company, a corporation of New York

Filed Dec. 22, 1960, Ser. No. 63,306

Term of patent 14 years

(Cl. D52—6)

FIG.1

FIG. 2

FIG. 1 is a perspective view of a panel meter for an ammeter or the like, showing my new design; and

FIG. 2 is a side elevational view thereof, the opposite side having substantially the same appearance.

The dominant features of my new design are shown in solid lines in the drawings.

I claim:

The ornamental design for a panel meter for an ammeter or the like, as shown and described.
